UNITED STATES PATENT OFFICE.

EDWARD J. QUINN, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

GUIDE FOR ROLLING-MILLS.

1,173,738.

Specification of Letters Patent. Patented Feb. 29, 1916.

Application filed January 23, 1914. Serial No. 813,903.

To all whom it may concern:

Be it known that I, EDWARD J. QUINN, a citizen of the United States, residing at Worcester, in the county of Worcester and 5 Commonwealth of Massachusetts, have invented a new and useful Improvement in Guides for Rolling-Mills, of which the following description, taken in connection with the accompanying drawings, is a specification.

The present invention relates to a guide designed to support the rod or bar fed to the rolls of a rolling mill in proper position to present the same to the circumferential 15 grooves or passes of the rolls. It has heretofore been found advantageous to employ a pair of coöperating guide plates, having opposed recesses in their adjacent faces, adapted to constitute a guiding aperture for 20 the rod or bar, and to make such guide plates adjustable toward and away from one another, for the purpose of varying the size and shape of the aperture formed by their recesses, in order to accommodate different 25 sizes and shapes of bars. Such adjustment has heretofore been accomplished by an adjusting screw, adapted to bear against, and thereby retain in adjusted position, one of 30 said plates. However, on account of the necessity of positioning such plates in close proximity to the rolls, it has been found difficult heretofore to operate and support such a screw in favorable position to exert 35 pressure against the adjustable guide plate at the most effective point in the same. The present invention aims to overcome this difficulty; and it is a further object of this invention to provide means for holding the adjustable guide plate which, while adapted to 40 retain and hold said plate quite as effectively as a screw in direct contact therewith, possesses a certain degree of resilience, which is favorable to the travel of the bar through the aperture formed by the opposed recesses 45 of the guide plates.

Referring to the accompanying drawings, Figure 1 is a side view of a rolling mill-housing, provided with a guide embodying my present invention, the latter being shown 50 partially in longitudinal section. Fig. 2 is a section on line 2—2, Fig. 1.

Like reference numerals refer to like parts in the different figures.

Referring to the drawings, 1 denotes a roll 55 housing having journaled therein an upper

roll 2 and a lower roll 3. Said rolls are provided with the usual circumferential grooves or passes, that in the lower roll 3 being shown at 4, Fig. 2. In front of the rolls and rigidly supported on a transverse portion 5 of the housing 1 is a supporting frame 6, which in the present instance takes the form of an open ended trough-like structure, providing an interior chamber 7 for the reception of the mechanism embodying this invention. The said supporting frame has side walls 8 and 9, which are extended forwardly into close proximity to the rolls 2 and 3. A pair of guide plates 10 and 11, provided on their adjacent faces with opposed recesses to substantially embrace the bar 12, are received within the forward end of the chamber 7, and project forwardly therefrom into close proximity to the rolls 2 and 3. In the present instance, the bar 12 is elliptical 65 in cross section with its major axis vertical, as shown in Fig. 1, and its contact with the recesses of the guide plates 10 and 11 restrains it from shifting or tilting sidewise as it is presented to the rolls. The guide plate 10 bears against the vertical wall 8 of the supporting frame 6, and the guide plate 10 is held against the bottom of the frame 6 by a screw passing through the top wall of the frame 6, shown at 13, Fig. 1. The plates 70 10 and 11 are held from longitudinal movement by ribs 10^a entering a recess 10^b in the bottom of the frame 6. The guide plate 11 is free to be moved toward or away from the guide plate 10 for the purpose of varying 75 the size of the guide way formed by the co-operating recesses of said plates. The apparatus for effecting the said adjustment of the plates and for applying a pressure to the plate 11, comprises a screw 18 held in the side wall 9 and rotated by a lever handle 20. 80

On account of the location of the plates 10 and 11 at the extreme forward end of the supporting frame 6, whereby for a substantial portion of their lengths they project 85 outwardly of said frame, the use of a screw, large enough for the purpose and bearing against the center of the plate 11, as in previous constructions is precluded by reason of the reduced size of the supporting frame 90 at such a point. To obviate this objection a lever 15, comprising a plate of substantially the same width as the height of the guide plate 11, is mounted edgewise within 95 said chamber, being pivoted on a bolt 16 100 105 110

mounted at the rear end of the frame, and extending forwardly to contact with the central portion of the guide plate 11 by means of a projecting ledge 17. At a point 5 intermediate its ends, the lever 15 is engaged by the adjusting screw 18, adapted to be moved in or out by means of the operating handle 20 which is held on the hexagonal shank 21 of the screw 18, or any suitable 10 connection may be provided.

It will be noted that the provision of the lever 15 enables the adjusting screw to be located at a point removed from the guide plates 10 and 11, and also at a convenient 15 and practicable distance from the rolls, so as to permit of its ready operation. Furthermore, owing to the increased leverage which obtains at the forward end of the lever, a smaller degree of movement will be 20 required for the screw than if it were in direct engagement, with the guide plate 11, as will be readily apparent. In addition, by reason of the lever being placed on edge, an effect similar to that of a stiff leaf spring 25 is secured, whereby the passage of the bar between the guide plates is rendered freer, than if the plate 11 were held absolutely rigid.

I claim,

30 1. In a guide for rolling mills, a fixed guide plate and an adjustable guide plate, and yielding means contacting with said adjustable guide plate to retain said plate against the bar which is being rolled.

35 2. In a guide for rolling mills, a supporting frame, a fixed guide plate and an adjustable guide plate, each having interlocking engagement with said supporting frame, and yielding means for retaining said adjustable guide plate in operative relation to said fixed guide plate.

40 3. In a guide for rolling mills, a pair of coöperating guide plates, an adjusting member for one of said guide plates, and a resilient connection between said guide plate and said adjusting member.

45 4. In a guide for rolling mills, a support-

ing frame, a pair of coöperating guide plates carried thereby, and a member adjustably mounted in said supporting frame, at a point longitudinally offset from said guide plates, for varying the distance between said plates.

5. In a guide for rolling mills, a pair of guide plates, a lever contacting with one of said plates, and means for moving said lever against said guide plate.

6. In a guide for rolling mills, a pair of guide plates, a lever contacting with one of said plates, and means for exerting pressure against said lever between its ends and at a point remote from said guide plate.

7. In a guide for rolling mills, a supporting frame, a pair of guide plates carried thereby, an adjusting screw carried by said frame beyond the end of one of said guide plates, and means for transmitting movement of said screw to one of said guide plates.

8. In a guide for rolling mills, a supporting frame, a pair of guide plates carried thereby, an adjustable member carried by said frame, and resilient means for transmitting movement of said member to one of said guide plates.

75 9. In a guide for rolling mills, a supporting frame, a pair of guide plates carried thereby, an adjustable member movable in said frame, and adapted to move one of said guide plates, and means between said adjustable member and said last mentioned guide plate for multiplying the movement of the adjustable member.

10. In a guide for rolling mills, a supporting frame, a pair of guide plates carried thereby, an adjusting member movable in said frame, and pivoted means for transmitting the movement of said adjusting member to one of said guide plates.

Dated this 19th day of January, 1914.

EDWARD J. QUINN.
